UNITED STATES PATENT OFFICE.

LAWRENCE F. WOODHEAD, OF ROSWELL, TERRITORY OF NEW MEXICO.

DEVICE FOR HOLDING AND DISPENSING PINS.

No. 909,270.

Specification of Letters Patent.

Patented Jan. 12, 1909.

Application filed May 8, 1908. Serial No. 431,185.

To all whom it may concern:

Be it known that I, LAWRENCE F. WOODHEAD, citizen of the United States, residing at Roswell, in the county of Chaves and Territory of New Mexico, have invented certain new and useful Improvements in Devices for Holding and Dispensing Pins, of which the following is a specification.

This invention contemplates certain new and useful improvements in devices for holding and dispensing pins, and the object of the invention is an improved device of this character which may be employed with pins of different lengths, and which is arranged to feed the pins in regular succession to a discharge plate, from which they may be readily released by peculiar means, so as to fall into the outstretched hand of the user.

With this and other objects in view that will more fully appear as the description proceeds, the invention consists in certain constructions and arrangements of the parts that I shall hereinafter fully describe and then point out the novel features thereof in the appended claims.

For a full understanding of the invention and the merits thereof, and to acquire a knowledge of the details of construction and the means for effecting the result, reference is to be had to the following description and accompanying drawings, in which:

Figure 1 is a side elevation of my improved pin holder showing the latter mounted upon the stand; Fig. 2 is a front elevation thereof; Fig. 3 is a similar view illustrating the manner of mounting the holder in a desk; Fig. 4 is an enlarged perspective view, illustrating one method of loading the magazine; Fig. 5 is a vertical longitudinal section of the pin holder; Fig. 6 is a rear elevation thereof; Fig. 7 is an enlarged perspective view of the discharge plate and the lower portion of the chute; Fig. 8 is a detail view of the throat; Fig. 9 is an enlarged sectional view on the line 9—9 of Fig. 5; and, Fig. 10 is an enlarged detail view of the chute.

Corresponding and like parts are referred to in the following description and indicated in all the views of the drawings, by the same reference characters.

My improved pin holder embodies a casing which consists of a front 1 and two sides 2 perpendicularly and rearwardly disposed to the front, and in which is mounted in a rearwardly inclined position a magazine chute 3,

that is in the form of a tube and is split longitudinally on its lower side and formed at its separated edges with depending spaced flanges 4. The chute is detachably supported at its upper end by a cross piece 5 which extends between the sides 2 near the upper rear corners thereof, and is curved intermediate of its ends so as to partially encircle the chute. The chute is rigidly secured at its lower end to a discharge plate 7, 65 and in the present instance is recessed in its flanges 4, as indicated at 6, so as to embrace the rear portion of said discharge plate 7, which is mounted in a slightly rearwardly inclined position in the casing, and extends 70 transversely between the sides 2, with its ends resting on and supported by inwardly disposed lugs 8 that are carried by the sides. This discharge plate 7 is formed with a slot 9 that leads forwardly from the rear edge 75 thereof in registry with the chute, and has its forward end substantially perpendicularly disposed, as indicated at 10, with its extremity enlarged, as shown at 11. The discharge plate 7 is formed on the opposite side 80 of the slot 9 from the angularly disposed end 10, with a plurality of depending ears 12 in transverse alinement with the latter, and a plunger 13 is loosely mounted in such ears, with its outer end extending through the 85 corresponding side 2 of the casing, and formed with an enlarged head 14. The inner extremity of this plunger is normally held in spaced relation to the slot 9, and for this purpose a coil spring 15 is secured beneath the 90 plate 7 by means of lugs 16 punched or otherwise formed in the plate and engaging one end of the spring, the other end of said spring bearing against and exerting an outward pressure upon an inwardly facing shoulder 17 95 formed by reducing the inner end of the plunger, as shown.

The magazine chute 3 is designed to receive and carry the pins which depend therein, as shown, with their heads in the tubular portion of the magazine, the said pins feeding toward the lower end of the magazine, owing to the inclination of the latter, and the lowermost pin being carried by gravity into the slot 9 of the discharge plate, and being suspended therein at the juncture of the main portion of the slot with the angularly disposed end 10 thereof. The portions of the flanges 4 of the magazine chute which extend between the upper end thereof and the 110

discharge plate 7 are preferably corrugated, as indicated at 18, so as to form a winding passage to effectually prevent the pins moving downwardly in the magazine from 5 buckling and thus blocking the latter.

- In order to prevent the lowermost pin from accidentally passing through the angularly disposed end 10 of the slot, when the device is being moved about, I provide a spring 19, 10 one end of which is rigidly secured to the discharge plate in front of said end 10 and the other or free end of which is rearwardly disposed and normally bears against a lug 19^a depending from the discharge plate. When 15 the free end of the spring is in this position it extends across the end 10 of the slot, in alignment with the adjacent wall of the main portion thereof, and thus prevents the pin from accidentally passing through said end 10. 20 The movement of the lowermost pin is preferably further limited by a stop 4^a formed by bending the lower extremity of the flange 4 opposite to the end 10 of the slot, laterally in alignment with the forward wall thereof. 25 In the practical use of my improved device the head 14 is pressed by the user, so as to move the plunger 13 inwardly against the tension of the spring 15, and cause the inner extremity of said plunger to pass through the 30 recess 6 and abut against the pin that is positioned in the slot in the discharge plate and move the pin transversely against the tension of the spring 19, through the angularly disposed end 10 into the enlarged portion 11 of 35 said slot, through which the head of the pin readily passes and is thus released from the discharge plate and falls into the outstretched hand of the user of the device. The plunger 13 is automatically retracted by the spring 15 40 which returns the plunger to its normal position in spaced relation to the slot 9, and thus permits the next succeeding pin to fall into position in the slot in the discharge plate, and the free end of the spring 19 to return to its normal 45 position to prevent the accidental movement of said pin. It will thus be seen that one pin is always in readiness to be removed, and the above operation may be repeated as often as desired, until the supply of pins in 50 the magazine is exhausted.
- In order to collect the pins which are not desired for use, the front 1 of the casing is formed with a forwardly disposed inwardly opening hopper 20 which leads into a throat 55 21 secured to the inner surface of the front and extending downwardly and rearwardly therefrom, with its lower end preferably bell-shaped, as indicated at 22. This bell-shaped end of the throat is arranged to fit around the 60 upper end of a supplementary tube 23 which is mounted in the casing in an oppositely inclined position to the chute 3, and is substantially similar to the latter, excepting that its lower end is closed. The supplementary tube 65 is detachably secured in the casing by

means of a spring clip 24 which is secured to one of the sides 2 and projects inwardly therefrom, and is arranged to partially encircle the supplementary tube between the ends thereof. The pins may be fed into the hopper 20, either head or point first, and pass through the throat 21 into the supplementary tube 23, and move toward the lower end of the latter, because of the inclination of the same. 70

When it is desired to replenish the supply of pins in the magazine chute, the supplementary tube is detached from the spring clip 24, and is held in an oppositely inclined position with its open end inserted in the upper end of the chute, which is preferably slightly enlarged at this end, as shown at 3^a, so that the pins pass from the supplementary tube into the magazine chute to load the same. Another method of loading the magazine chute is illustrated in fig. 4, in which a separate loading tube 31 is employed, this tube being substantially similar to the supplementary tube 23 except that its flanges are not corrugated. A paper of pins is fed into the loading tube and the paper holder is slipped downwardly between the spaced flanges thereof to effectually and quickly strip the pins from their holder and leave them depending in the loading tube, which is then applied 90 to the magazine chute in an inclined position to transfer the pins thereto. 95

The sides 2 of the casing are formed at their outer edges with outstanding flanges 25 arranged for engagement with the returned edges of a top 26 to detachably secure the latter to the casing. This top is preferably formed with a sleeve 27 which is designed to be mounted upon the outwardly projecting arm 28 of a stand 29, so as to suspend the 100 device from the same, said sleeve being adjustably secured upon the arm by means of a screw 30 passing therethrough. If desired, the top 26 may be screwed or otherwise secured to a horizontal partition of a desk, to 105 detachably suspend the casing from the latter. 110

Having thus described the invention, what I claim is:

1. A pin holder comprising a discharge 115 plate formed with a slot having an angularly disposed end the extremity of which is enlarged, a support for the discharge plate, means for feeding the pins in regular succession into the slot, so that they will be suspended therein in registry with the angularly disposed end of said slot, and means for moving the pins through the angularly disposed end of the slot into the enlarged portion thereof, whereby to release the pins from 120 the discharge plate. 125

2. A pin holder comprising a discharge plate formed with a slot having an angularly disposed end, the extremity of which is enlarged, means for supporting the discharge 130

plate, means for feeding the pins in regular succession into the slot, so that they will be suspended therein in registry with the angularly disposed end of said slot, and a plunger 5 movably mounted upon the discharge plate and arranged to abut against the pins to carry the same through the angularly disposed end of the slot into the enlarged portion thereof.

10 3. A pin holder comprising a discharge plate formed with a slot leading from one edge thereof, the end of said slot being angularly disposed, and the extremity of the latter being enlarged, a support for the discharge plate, a chute having its lower end in registry with the slot and arranged to feed pins successively into the same, so that they are suspended therein in registry with the angularly disposed end of the slot, and a plunger 15 movably mounted upon the discharge plate and arranged to abut against the pins to carry the same through the angularly disposed end of the slot into the enlarged portion thereof.

20 4. A pin holder comprising a discharge plate formed with a slot leading from one edge thereof, the end of said slot being angularly disposed, and the extremity of the latter being enlarged, a support for the discharge plate, a chute having its lower end in registry with the slot and arranged to feed the pins successively into the latter, so that they are suspended in the slot in registry with the angularly disposed end, said discharge plate being formed on the opposite side of the slot 25 from the angularly disposed end with depending ears in alinement with the latter, a plunger movably mounted in the ears and designed to abut against the pins and carry them through the angularly disposed end of the slot into the enlarged portion thereof, and means for automatically retracting the plunger, as and for the purpose specified.

30 5. A pin holder comprising a discharge plate formed with a slot leading from one edge thereof, the end of the slot being angularly disposed and the extremity thereof being enlarged, means for feeding the pins in regular 35 succession into the slot, so that they will be suspended therein in registry with the angularly disposed end of the slot, means for preventing said pins from moving accidentally through the angularly disposed end of the slot, and means for moving the pins through the angularly disposed end of the slot into the enlarged portion thereof, whereby to release the pins from the discharge plate.

40 6. A pin holder comprising a discharge plate formed with a slot having an angularly disposed end, the extremity of which is enlarged, means for supporting the discharge plate, means for feeding the pins in regular 45 succession into the slot, so that they will be suspended therein in registry with the angularly disposed end of said slot, a plunger movably mounted upon the discharge plate

and arranged to abut against the pins to carry the same through the angularly disposed end of the slot into the enlarged portion thereof, and means for automatically retracting the plunger.

70

7. A pin holder comprising a discharge plate formed with a slot, one end of which is angularly disposed and has an enlarged portion, a support for the discharge plate, a chute having its lower end in registry with the slot and arranged to feed the pins successively into the latter, so that they are suspended in the slot in registry with the angularly disposed end, said discharge plate being formed on the opposite side of the slot 75 from the angularly disposed end with depending ears in alinement with the latter, a plunger movably mounted in the ears and designed to abut against the pins and carry them through the angularly disposed end of the slot into the enlarged portion thereof, and means for automatically retracting the plunger, as and for the purpose specified.

80

8. In a pin holder, a tubular chute split longitudinally and formed at its separated edges with depending flanges, the pins being suspended between the said flanges and feeding toward the lowermost end of the chute, the flanges being corrugated to form a winding passage, as and for the purpose specified.

90

9. A pin holder comprising a casing, a discharge plate mounted within the casing and formed with a slot leading from one edge thereof, the end of the slot being angularly disposed and the extremity thereof being enlarged, means for feeding the pins in regular succession into the slot, so that they will be suspended therein in registry with the angularly disposed end of the slot, means for preventing said pins from moving accidentally through the angularly disposed end of the slot, and means for moving the pins through the angularly disposed end of the slot into the enlarged portion thereof, whereby to release the pins from the discharge plate.

100

10. A pin holder comprising a discharge plate formed with a slot leading from one edge thereof, the end of said slot being angularly disposed and the extremity thereof being enlarged, a support for the discharge plate, means for feeding the pins in regular succession into the slot so that they will be suspended therein in registry with the angularly disposed end of the slot, means for moving the pins through the angularly disposed end of the slot into the enlarged portion thereof, and a spring secured to the discharge plate and extending across the angularly disposed end of the slot, as and for the purpose specified.

110

11. A pin holder comprising a tubular chute split longitudinally and formed at its separated edges with depending spaced flanges, the pins being suspended between such flanges and feeding toward the lowermost

120

125

end of the chute, and means for discharging the pins one at a time from the lower end of the chute, the flanges of the chute being corrugated to form a winding passage, and the lower extremity of one of the flanges being angularly disposed to form a stop, as and for the purpose specified.

In testimony whereof I affix my signature in presence of two witnesses.
